UNITED STATES PATENT OFFICE.

MARTIN T. C. JENTER, OF MOUNT VERNON, NEW YORK.

METHOD AND MOUNTING FOR ADVERTISING DISPLAYS.

Application filed August 15, 1924. Serial No. 732,240.

To all whom it may concern:

Be it known that I, MARTIN T. C. JENTER, citizen of the United States, and resident of Mount Vernon, in the county of West-
chester and State of New York, have invented certain new and useful Improvements in Methods and Mountings for Advertising Displays, of which the following is a specification.

10 My present invention relates to a novel structure and method of mounting, for advertising displays, and has for one of its objects the quantity manufacture of an economical, collapsible type of stand for supporting, when in display position, one, or a plurality of display signs, the device when in collapsed position, being easily packed for shipment.

15

My invention further comprehends the method of utilizing a group, or series of groups of cooperating cut-out displays so as to permit the building up of a scenic or stage effect, more especially in conjunction with an actual article of commerce such as 25 an electric sadiron, shoes, etc., thereby to prominently display and accentuate the article offered for sale. This form of advertising includes in its scope counter displays and full store-window displays, and my device may also be utilized in a number of 30 other ways for this purpose.

Another advantage of my device is the provision of a simple means whereby a plural display or scene may be built up from 35 any desired number of cooperating display cards, to suit desire, and to support these aggregates in proper display position without having to resort to placing any special means on the display cards themselves.

40 In the drawings, Fig. 1 is a perspective view of the collapsing stand set up;

Fig. 2 is a plan view of Fig. 1;

Fig. 3 is a rear view;

Fig. 4 is a rear view collapsed;

45 Fig. 5 is a fragment of the card rack in perspective;

Fig. 6 shows two cooperating display cards in relative position out of the rack; and

50 Fig. 7 is a fragmentary plan view of a series of cards racked in relative position.

My stand, generally denoted by 1, Fig. 1, comprises a base piece 2, having hingedly mounted, on opposite ends by hinges 3 and

55 4, two movable card rack uprights 5 and 6. The front edges of these uprights, which,

in conjunction with the base piece, are of wood, are each provided with metal card rack pieces 7 and 8, these being of a stock channel section, for economy, and are 60 screwed to or otherwise affixed in operative relation to the front edges of the uprights as shown in Fig. 1. These channels, as shown, may be double but they may also be single, and they admit of the support, when 65 in operative relation, of a plurality of show cards or advertising display signs, as will be hereinafter described.

Inasmuch as the uprights 5 and 6 are hingedly mounted for permitting of the collapsing of the device, means such as pivoted struts 10 and 11 are mounted upon the base piece, and being provided with slots S at their upper ends, they are easily engaged or disengaged with the holding lugs or 70 screws 8' and 9' which are in each of the uprights as is shown in Fig. 3, and by these two strut means, the uprights are held against collapse when so desired, and folded 75 completely out of the way when the device 80 is in the collapsed position.

By referring to Figs. 3 and 4, it will be observed that the hinge 3 on the side piece 5, is mounted upon a pad piece 12, which is affixed to said side piece. This method of 85 mounting the hinge, in effect, causes said side piece to be offset, or raised, when in folded position, so that, when the side pieces are folded down as shown at Fig. 4, the side piece 5, is superposed upon the side piece 6, 90 in a parallel symmetrical manner.

As a means for permitting the mounting of wide cards and the like in the desired display position such as is indicated at A to D inclusive, Fig. 7, especially when single displays are used, I have provided a detachable resilient tie 9 which is connected between the uprights 5 and 6 and spaced away from the front edges of the uprights and in such manner that it can be readily unhooked 95 when folding the device. The use of this device, which consists, mainly, of a coil spring having two tie ends T on opposite ends which engage the uprights, is to create a tension between the uprights thereby to 100 keep the uprights under stress, to prevent unloosening of the struts 10 and 11, when erected, and to permit the springing of the tension means 9 when a wide card is sprung 105 into the rack for support. This is illustrated in Fig. 2 wherein the card B shown in dotted lines is engaged in the channels of 110

the opposite uprights but is sprung or curved in such manner that its back rests against the spring 9, thereby holding this card in the desired position. Larger cards will cause 5 the tension means to be easily displaced, backwardly without interfering with its function.

When it is desired to collapse the stand, the two swing brackets or struts 10 and 11 10 are disengaged from their screws 8' and 9, and are swung downwardly in parallelism with the base 2, the spring 9 being unhooked at one end from one of the brackets as 6 which is folded downwardly, see Fig. 4, and 15 the upright 5 is swung inwardly and downwardly and the spring tucked under. It will, therefore, be seen that this makes a compact package for shipping.

In use, the device is opened erect as indicated in Fig. 1 and a display card B, Fig. 6, is introduced into the rack as indicated by the dotted lines at B, Fig. 2, the ends of the cards engaging in the channels C of the rack pieces 7 and 8. The card B may have on it 20 a single complete picture, or it may have on it just merely a component part of a collective picture, the remainder of which may be printed on a second sheet such as A, Fig. 6, which is in the form of a cut-out, and this 25 may be introduced into the channels C, as indicated at Figs. 2 and 6, both of these cards being sprung into the channel so that the springing tension of the cards will hold them in associated position, thereby making 30 a scenic effect.

As a part of the herein disclosed conception, the method of advertising an article of manufacture is another feature of advantage. In arranging a display, the scenic 35 display cards A and B, Fig. 6, may be so formulated in design as to emphasize, for instance, a perfume, as indicated by a bottle of this commodity as at 13. Fig. 6, which is mounted upon a pallet or extension 14, 40 which may be part of the card B, or may be a separately associated element. It is obvious, that a plurality of cards may be made and various forms of display advertising accomplished and the advertising features of the display be thereby enhanced.

A plurality of these cards, as indicated, 45 may be utilized as outlined in Fig. 7 in which a plurality of cards A, B, D and E are shown in operative position in engagement with the channel section C. Due to the collapsibility of the stand, which in actual practice is quite large, the stand and the component elements of the advertising display cards may be shipped together and 50 easily erected wherever desired.

It is understood that I do not desire to 55 be held to the exact details of construction herein shown, and that modifications may be made without departing from the general scope of the invention as herein claimed.

Having thus described my invention, what I claim is:

1. A display stand of the class described, comprising in combination, a base piece, card display holding uprights hingedly 70 mounted thereon, means for locking said display in open position, and a resilient detachable tie between said uprights.

2. In combination with a base piece, two closable card supporting uprights thereon, 75 a card rack on each of said supports, and tensioning means between said closable elements.

3. A card rack of the class described, comprising in combination, a base having card display racks thereon, said racks being mounted upon hinged side pieces, means associated with said base piece and said side pieces whereby to hold the same upright, 80 and resilient means associated between said side pieces whereby to cooperate with said first means to hold said side pieces in said upright position.

4. A card rack of the class described, comprising in combination, a base having 85 card display racks oppositely disposed thereon, said racks being mounted upon hinged side pieces, means associated with said base piece and said side pieces whereby to hold the same upright, and resilient 90 means associated between said side pieces whereby to hold the same under tension.

5. In a card display device of the class described comprising, in combination, a base piece having two hingedly mounted side 95 pieces thereon, card racks on said side pieces, pivoted detachable struts for holding said side pieces in upright position, and tensioning means between said side pieces, one of 100 said side pieces having its hinge offset for the purpose of permitting symmetrical folding of the device when in collapsed position.

6. In a display device, in combination with a base and spaced uprights foldably mounted thereon, means for releasably maintaining 105 the uprights in upright spaced relation, bendable display means separable from the device, and means on the front edge faces of said uprights for holding said bendable means in bent display position at the front 110 of the device.

7. In a display device, in combination with a base and spaced uprights foldably mounted thereon, means for releasably maintaining 120 the uprights in upright spaced relation, bendable display means separable from the device, and means on the front edge faces of said uprights for holding said bendable means in inwardly bent display position between said uprights.

8. In a display device, in combination with a base and spaced uprights foldably mounted thereon, means for releasably maintaining 125 the uprights in upright spaced relation, releasable spring tensioning means on the in- 130

- ner sides of the uprights and spaced away from the front edges thereof for connecting the uprights, bendable display means separable from the device, and means located 5 on the front edges of the uprights for holding said bendable means in inwardly bent display position between the uprights, said bendable display means when in inwardly bent display position resting at the back of 10 said means against said connecting means.
9. In a display device, in combination with a base and spaced uprights foldably mounted thereon, means for releasably maintaining the uprights in upright spaced relation, retaining means on the front edge faces of the 15 uprights, and a plurality of associated bendable display members separable from the device some of which are cut out display members, some of said associated members 20 being removably retained by said means in inwardly bent display position and others thereof being removably retained in outwardly bent display position between said uprights.
- 25 10. In a display device, in combination with a base and spaced uprights foldably mounted thereon, means for releasably maintaining the uprights in upright spaced relation, releasable spring tensioning means on 30 the inner sides of the uprights and spaced away from the front edges thereof for connecting the uprights, retaining means appurtenant to the front edges of the uprights, and a plurality of associated bendable 35 display members separable from the device some of which are cut-out display members, some of said associated members being removably retained by said means in inwardly bent display position and others thereof being 40 removably retained in outwardly bent display position between said uprights, the innermost of the inwardly bent members resting at its back against said connecting means, all of said members except the innermost 45 thereof being cut-out display members.
11. In a display device, in combination, a base piece, supports hingedly attached at their lower ends to the base piece and spaced
- apart on the base piece and movable from collapsed position to vertical position thereon, bendable display means of greater length than the distance between the supports when the supports are in vertical position, and means on the front edge faces of the supports cooperating with the side edges of the display means for removably retaining the display means in bent display position between the supports when the supports are 50 in vertical position.
12. In a display device, in combination, a base piece, supports hingedly attached at their lower ends to the base piece and spaced apart on the base piece and movable from collapsed position to vertical position thereon, bendable display means of greater length 55 than the distance between the supports when the supports are in vertical position, and channel members on the front edge faces of the supports for receiving the side edges of the display means for removably retaining the display means in bent display position between the supports when the supports are in vertical position.
13. In a display device, in combination, a base piece, supports hingedly attached at 60 their lower ends to the base piece and spaced apart on the base piece and movable from collapsed position to vertical position thereon, and means cooperating between said hingedly attaching means and one of the 65 supports for permitting the supports when in collapsed position to lie in parallel horizontal relation to each other.
14. In a display device, in combination, a base piece, supports hingedly attached at 70 their lower ends to the base piece and spaced apart on the base piece and movable from collapsed position to vertical position thereon, and a pad piece on one of the supports for permitting the supports when in collapsed position to lie in parallel horizontal 75 relation to each other.

Signed at Mount Vernon in the county of Westchester and State of New York this 25th day of March A. D. 1924.

MARTIN T. C. JENTER.
